ATTORNEY.

UNITED STATES PATENT OFFICE.

JAMES P. KELLY, OF ALEXANDRIA, INDIANA.

DESIGN FOR AN AX.

SPECIFICATION forming part of Design No. 26,513, dated January 12, 1897.

Application filed August 29, 1896. Serial No. 604,834. Term of patent 14 years.

To all whom it may concern:

Be it known that I, JAMES P. KELLY, a citizen of the United States, residing at Alexandria, in the county of Madison and State of Indiana, have invented and produced a new and original Design for Axes, of which the following is a specification.

The object of my said invention is to produce a new design for the surface ornamentation of axes, whereby they are rendered highly attractive in appearance.

Said design consists in an ax the surface of which is composed of separate fields or sections of different colors, that portion *a* immediately adjacent to the cutting edge being of one color, the general surface *b* being of another color, except two segments or "bevels" *c* above the edge and below the poll of the ax, between which a narrow tongue of the general surface extends, said two segments

or bevels being of still another color, all as indicated in the accompanying drawing, which shows an ax the side of which has the said ornamental pattern or design thereon and which may be formed thereon in any desired manner. 25

Having thus fully described my said invention, what I claim as new, and desire to secure by Letters Patent, is—

The design for an ax having the ornamental surface pattern described, the several portions thereof being of contrasting colors, substantially as shown and described. 30

In witness whereof I have hereunto set my hand and seal, at Indianapolis, Indiana, this 11th day of July, A. D. 1896. 35

JAMES P. KELLY. [L. S.]
